UNITED STATES PATENT OFFICE.

OSCAR L. SWALLOW, OF FORT WORTH, TEXAS.

CENTER RAIL FOR KEY-ACTIONS.

1,319,188.

Specification of Letters Patent. Patented Oct. 21, 1919.

Application filed March 20, 1919. Serial No. 283,796.

To all whom it may concern:

Be it known that I, OSCAR L. SWALLOW, a citizen of the United States, residing at Fort Worth, in the county of Tarrant and 5 State of Texas, have invented a new and useful Center Rail for Key-Actions, of which the following is a specification.

This invention relates to center rails for the keys of keyboards such as form parts of 10 pianos, and like instruments.

An object of the invention is to do away with the center pins ordinarily employed; to eliminate the guide pins on the front rail; and to dispense with the chiseling heretofore necessary to provide holes for bushings.

Another object is to provide a center rail which extends over the keys and can be adjusted easily.

20 A further object is to provide a structure which will prevent the keys from rattling and turning sidewise and which is more simple in construction and more durable than the constructions heretofore used.

25 With the foregoing and other objects in view which will appear as the description proceeds, the invention consists of certain novel details of construction and combinations of parts which will be hereinafter more

30 fully described and pointed out in the claims it being understood that various changes may be made in the construction and arrangement of parts without departing from the spirit or sacrificing any of the advantages of the invention as set forth in the 35 appended claims.

In the accompanying drawings the preferred form of the invention has been shown.

40 In said drawings—

Figure 1 is a rear elevation of a portion of the rail and adjacent parts, some of the keys of the keyboard being shown connected thereto, said keys being in section on the 45 line 1—1, Fig. 3.

Fig. 2 is a similar view of the front of the rail and adjacent parts, the keys being in section on the line 2—2, Fig. 3.

Fig. 3 is a view partly in side elevation 50 and partly in section of one of the keys, the rail being shown in section.

Fig. 4 is a detail view of one of the 55 hangers or flanges.

Referring to the figures by characters of

reference, 1 designates end posts having 55 vertical slots 2 in their upper ends for the reception of screws 3 which engage the end portions of the center rail 4. The front face of the rail 4 is formed with an overhanging longitudinal shoulder 5 and an inwardly extending groove in line with the shoulder, as shown at 6. Hangers or flanges 7 are adapted to be secured to the front face of the rail and each is formed of a single strip of metal folded to form a 65 loop 8 while end lapping end portions of the strip are slotted as at 9 for the reception of fastening screw 10. Ears 11 extend rearwardly from the upper end of the back thickness of the hanger or flange and project into the groove 6, the upper end of the other thickness of the said hanger abutting against the shoulder 5. Thus the hanger is held securely and cannot swing laterally or toward or from the rail. The 70 lower or loop end of the hanger is preferably reduced in width so as to enter readily an opening 12 formed in the key 13, where it is connected to the key by a pin 14.

By loosening the screws 3 the rail 4 can 80 be raised or lowered, thereby changing the dip of all the keys.

What is claimed is:—

1. The combination with posts, of a rail 85 connected to the posts for up and down adjustment, there being a longitudinal groove within the rail, hangers secured to the rail and having ears extended into the groove, and keys extending under the rail and pivotally connected to and supported by the 90 respective hangers.

2. The combination with posts, of a rail 95 connected to the posts for up and down adjustment, there being a longitudinal shoulder and groove upon the rail, hangers secured to the rail and abutting against the shoulder, ears upon the hangers and fitted snugly within the groove, keys extending under the rail, and pivotal connections between the hangers and the respective keys. 100

In testimony that I claim the foregoing as my own, I have hereto affixed my signature in the presence of two witnesses.

OSCAR L. SWALLOW.

Witnesses:

J. E. KNIGHT,
Z. MESTRALLET.
